UNITED STATES PATENT OFFICE

THOMAS BRADY, OF EAST ORANGE, NEW JERSEY, ASSIGNOR TO OTIS ELEVATOR COMPANY, OF NEW YORK, N. Y., A CORPORATION OF NEW JERSEY

CLOSURE OPERATING MECHANISM

Application filed February 5, 1930. Serial No. 426,034.

The invention relates to closure mechanism and particularly to mechanism for operating closures controlling access to an elevator car and to mechanism for interlocking 5 closures with the control of the elevator car.

It has been found desirable to operate the hatchway doors and the car gates of elevator plants by power mechanism, particularly in installations in which such closures must be 10 frequently operated or in which their manual operation is inconvenient. Such power mechanism may be employed to effect both the opening and closing of the closures or may be employed to effect operation of the 15 closures in only one direction. Also, such mechanism may be employed to operate both the hatchway doors and the car gate or to operate either of them. In the case of the hatchway doors, it is of considerable ad- 20 vantage that the same power mechanism be employed to operate all of the doors of a particular installation as this avoids duplication of power devices at each of the landings served. In such cases it is of advantage that 25 the doors be disconnected from the power device and the operation of a hatchway door be effected by coupling the door at the landing at which a stop is made to the power mechanism. It is also of advantage, in cases 30 where both the car gate and hatchway doors are power operated, that the same power device be employed for operating the car gate that is employed for operating the hatchway doors. When the mechanism for operating 35 the hatchway doors and car gate is common to the doors and the gate, it is desirable that such mechanism be carried by the elevator car, particularly as such arrangement lends itself to simplicity of construction of door 40 and gate operating mechanism. Where the same power device is employed to operate the car gate as well as the hatchway doors, it is also of advantage that the car gate be dis- 45 connected from the power device and cou- 50 pled thereto when the operation of the gate is to be effected. The invention, in part, is directed to power operating mechanism for a closure of an elevator system in which the mechanism is disconnected from the closure 55 and in which the operation of the closure by

the operating mechanism is effected by coupling mechanism and closure together.

It is also advantageous when power devices are employed to operate the closures affording access to the car that checking devices be provided to bring them to rest easily and quietly. It is preferable that such checking mechanisms may be readily adjustable to suit the requirements of the closure in various installations in order that a separate 60 checking mechanism need not be designed for each installation. 55

It is also desirable, particularly in elevator installations in which the operation of the elevator car is under the control of the passengers or intending passengers themselves, that suitable interlocking mechanisms be provided to prevent the operation of the car when the car gate or any of the hatchway doors are in open position in order to lessen 65 the possibility of injury to passengers or prospective passengers. Such interlocking mechanisms for the hatchway doors comprise a locking mechanism for each hatchway door arranged to lock the door in closed position 70 and switching mechanism controlled by the locking mechanism for preventing the operation of the elevator car except when all the doors are locked in closed position. In connection with such interlocking mechanisms 75 it is preferable to provide suitable operating mechanisms therefor arranged to unlock the hatchway door at the landing at which a stop is to be made upon arrival of the car thereat. 80

Due to faults that may occur in the construction of buildings it is sometimes discovered in installing elevators that the clearances between the edge of the car and the hatchway doors are not uniform at various 85 landings. These variations in clearances present difficulties to the installation of auxiliary equipment, such as closure coupling and operating devices, on the elevator car and on the hatchway wall in that they reduce the available space for such equipment and 90 tend to interfere with the uniformity and positiveness of its operation. The invention is further directed to closure coupling and operating mechanisms adapted to overcome 95 these constructional defects and assure uni- 100

formity and positiveness of operation of the closures.

One feature of the invention resides in the provision of a power driven closure operating mechanism carried by the elevator car and normally disconnected from the car gate and hatchway doors in conjunction with electromagnetic means for coupling the car gate and the hatchway door at the landing at which the car is positioned to the closure operating mechanism for operation thereby.

A second feature resides in the provision of magnetic means for establishing and maintaining the coupling of a hatchway door to a closure operating mechanism carried by the elevator car regardless of variations in clearance between the hatchway doors and the elevator car.

A third feature resides in magnetically coupling a car gate to a power driven closure operating mechanism from which it is normally disconnected.

A fourth feature resides in preventing the operation of the closure operating mechanism to operate a closure unless the closure is effectively coupled to the closure operating mechanism.

A fifth feature resides in a coupling and operating mechanism for closures arranged to permit manual operation of the closures when desired.

A sixth feature resides in operating the interlocking mechanism for each hatchway door by the mechanism for coupling the hatchway door to the closure operating mechanism for operation thereby.

A seventh feature resides in preventing the operation of a closure operating mechanism to operate a closure unless and until the control circuits for the elevator car are interrupted to prevent its operation during the operation of a closure.

An eighth feature resides in the provision of an adjustable checking mechanism, and operating mechanism therefor, for retarding a closure in the final part of its movement.

Other features and advantages will become apparent from the specification, taken in connection with the accompanying drawings wherein one embodiment of the invention is illustrated.

In the embodiment of the invention to be described a closure operating motor is carried by the elevator car. This motor drives a carriage slidably mounted on the car for movement transversely of the entrance of the car. The hatchway doors at each landing are provided with movable armatures. Electromagnets mounted on the carriage act, upon energization, through their magnetic fields to attract the armature on the hatchway door, at the landing at which the car is positioned, to couple the hatchway door to the carriage for operation by the closure operating motor on the car. The invention

also contemplates operating the car gate, which is disconnected from the carriage and motor, through the magnetic fields of the electromagnets when the carriage is driven by the motor to operate the hatchway door.

A switching mechanism mounted on the carriage is arranged to be operated by the movable armature on the hatchway door upon its attraction to the carriage by the electromagnets. This switching mechanism controls the operation of the closure operating motor to prevent its operation except when the hatchway door is coupled for operation to the carriage. Suitable limit switches operable by the carriage are provided to terminate the operation of the motor for driving the carriage when the door and gate have been moved to open or closed position.

The armatures on each hatchway door are arranged when in unattracted position to lock the hatchway door in closed position and to control switching mechanism in the control circuits of the elevator car for preventing the operation of the elevator car when any hatchway door is unlocked. The interruption of the control circuits for the elevator car and the unlocking of the hatchway door at the landing at which the car is positioned is effected by the movement of the armature on the hatchway door upon its attraction by the electromagnets to couple the hatchway door for operation to the motor driven carriage on the car.

Checking mechanism is also provided to retard the gate and door in the final part of their opening and closing movements to insure that they will be brought to rest easily and quietly. This checking mechanism is adjustable to accommodate varying requirements of closure operation, such as variations in the extent of closure movement, in different elevator installations.

In the drawings:—

Figure 1 is a view, partly in section, of a portion of an elevator installation embodying the present invention illustrating the elevator car positioned adjacent a hatchway door, the coupling device being shown in inoperative position;

Figure 2 is a view of a portion of the elevator car and the adjacent hatchway door illustrating the coupling device in operating position, and the hatchway door locking mechanism in unlocked position, parts being shown in section to illustrate details of construction;

Figure 3 is a view taken along the line 3—3 of Figure 1 of a portion of the front of an elevator car embodying the coupling device of the present invention, with the movable carriage displaced from its operating position to facilitate illustration;

Figure 4 is a sectional view taken along line 4—4 of Figure 1 and illustrates the re-

- lation of the coupling device of the present invention to the car gate and a hatchway door and shows the hatchway door locking mechanism in locked position;
- 5 Figure 5 is an enlarged view of the switch on the carriage, parts being shown in section;
- Figure 6 is a section on line 6—6 of Figure 5;
- Figure 7 is an enlarged view, with parts in 10 section, of one of the limit switches for controlling the closure operating motor;
- Figure 8 is an enlarged view of the checking device illustrated in Figure 1, parts being shown in section;
- 15 Figure 9 is a sectional view taken along line 9—9 of Figure 8, illustrating details of construction; and
- Figure 10 is a diagram of a part of the 20 control circuits of an elevator system in which the operation of the car is controlled by an attendant illustrating the adaptation of the closure coupling and operating mechanism to such a system.
- Referring to the drawings, the elevator 25 car, designated 21, is raised and lowered in the hatchway by cables attached to the car sling, designated as a whole by 23. A support 24, substantially U-shaped in form, is secured to and extends between the side 30 members 25 of the car sling above the car and parallels the sides and front of the car. A gate 26 extending across the entrance of the car is suspended from hangers 27 provided with rollers 28 engaging a track 30.
- 35 The track is carried by a plate 29 mounted on support 24 and acts to guide the gate in movement transverse of the car entrance. Another support 31 is secured to channel members 32 fastened to the cross-head 33 of the car sling and supports a guide 34 extending across the car entrance. A third support 39 is mounted on plate 29 and carries a guide 20. A carriage 35, provided with rollers 36 engaging the guides 20 and 34, is 40 adapted to be moved relatively to the car entrance by a motor 37 mounted on the members 32. The shaft of motor 37 is provided with a sprocket 38. Sprocket 38 drives a second sprocket 41 through a chain 40.
- 45 Sprocket 41 is mounted on a shaft 42 journalled in a bearing support 43. The shaft 42 extends through bearing support 43 and carries a sprocket 44 connected to a similar sprocket 45 by a chain 48. Sprocket 45 is 50 mounted on a shaft 46 journalled in another bearing support 47. The bearing supports 43 and 47 are secured to the supports 31 and 39 and also serve as spacing members therefor. The upper tract of chain 48 is attached to carriage 35 so that, upon operation of motor 37 in either direction, the carriage is 55 moved transversely of the car entrance.
- Electromagnets 50 are mounted on plates 22 secured to angle members 51, preferably 60 of non-magnetic material such as brass, de-
- pending from carriage 35. The magnets 50 are mounted with their pole pieces positioned between the angle members 51. A plate 52 of magnetic material is mounted on a support 49 secured to the upright bars 59 of the sliding gate 26 and is positioned so as to be opposite magnets 50. Thus, upon energization of the magnets 50 the lines of force emanating from the magnets permeate the plate 52 to establish a magnetic coupling between the 65 gate and carriage 35. Upon movement of the carriage the magnetic coupling causes the gate to follow the carriage.
- A hatchway door 54 is provided at each 70 floor. Each door is suspended from hangers 55 provided with rollers 56 running on a track 57 supported in the door casing 58 so that the door 54 may be moved relatively to the door opening. The hatchway doors and their associated mechanisms are the same for 75 each floor and only the mechanism associated with a single door will be described.
- A plate 60 secured to the rear of the hatchway door is provided with projecting lugs 61 which serve as pivots for bell cranks 62. One 80 arm of each bell crank is pivotally connected to a member 63 which is of magnetic material. Member 63 serves as an armature for magnets 50 and is adapted to be attracted into close juxtaposition with the pole pieces of 85 the magnets, as illustrated in Figure 2, whenever the magnets are energized. The other arms of the bell cranks are pivotally connected to members 64 and 65 which are connected by a rod 66 guided through a lug 67 on plate 60. The arrangement of the connections of the armature 63 to plate 60 is such 90 that the weight of the armature normally maintains the latter in the position illustrated in Figure 1. Member 65 extends through a 95 guiding lug 70 on plate 60 and is connected at its lower end to a rod 68 which serves as a grip whereby the armature 63 may be manually raised when desired.
- The angle members 51 which are mounted 100 on and project from the carriage receive the armature 63 therebetween when the armature is attracted. This arrangement prevents the coupling of the door 54 to carriage 35 being 105 broken due to the possible occurrence of lateral motion of carriage 35 relatively to the armature on operation of the carriage by motor 37. Toothed rolls 80 are supported by brackets 69 mounted on the angle members 110 51. The rolls 80 are positioned between the angles 51 with their axes parallel to the path of movement of carriage 35. These rolls maintain the face of the armature a slight 115 distance away from the pole pieces of magnets 50. They also reduce the friction that 120 would result in the movement of carriage 35 longitudinally of the armature if the car is raised or lowered, as in a levelling operation, after attraction of the armature by the magnets. The face of the armature is covered 125 130

- by a leather strip 78 to obviate the possibility of noise due to contact of the armature with the rolls when the magnets attract the armature. The teeth of rolls 80 are cut transversely of their axes and are adapted to be imbedded in the leather strip 78 to aid in obviating the possibility of breaking the coupling due to side slippage of carriage 35 relative to the armature.
- 610 The armature 63 operates switching mechanism arranged in the control circuits; an operating roller 82 for the switching mechanism being positioned in the path of movement of the armature to be struck thereby when the armature is drawn to attracted position, see Figure 2. The construction of the switching mechanism is illustrated in Figures 5 and 6. This mechanism is arranged on a support 81 mounted between the plates 22.
- 615 The operating roller 82 is carried by a member 83 pivoted at 84 to support 81. The member 83 is connected by an insulated link 85 to one arm of a bell crank 86. Bell crank 86 is pivotally mounted in a housing 89 which is preferably of insulating material. The other arm 87 of the bell crank carries a contact 88. A spring 90 is electrically connected to a terminal 99 and acts on arm 87 to force contact 88 into engagement with a fixed contact 91 mounted in housing 89. Contact 91 is connected to a terminal 93. A second fixed contact 92 connected to a terminal 95 is yieldingly mounted in the housing 89 and is positioned to be engaged by contact 88. The armature 63 upon attraction by magnets 50 strikes roller 82, causing the contact 88 to be moved from engagement with contact 91 and into engagement with contact 92. Upon the return of the armature to unattracted position, spring 90 causes the disengagement of contact 88 from contact 92 and its reengagement with contact 91. Contact 88, in conjunction with contact 92, controls the circuit for motor 37 and, in conjunction with contact 91, controls the circuit for magnets 50, as will be described later.
- 620 The movement of carriage 35 to open and close the gate and door is terminated by the separation of contacts of limit switches 160 and 170, respectively adapted to control the circuits for motor 37. These switches are similar, the construction of switch 160 being illustrated in Figure 7. Referring to Figure 7, a lever 161 is pivoted on a support 162 mounted on base 163 of insulating material.
- 625 A contact 164 carried by one end of lever 161 is adapted to be forced into engagement with a contact 165 on base 163 by a spring 166 mounted between the support 162 and a lug on lever 161. Binding posts 167 and 168 are electrically connected to contacts 164 and 165 respectively. A roller 169 mounted on the other end of lever 161 is positioned to be engaged by a cam 171 on carriage 35 when the gate reaches open position. The engagement 630 of the cam and roller rocks lever 161 about support 162 and moves the contact 164 from engagement with contact 165. Switch 170 also is operated by cam 171, its roller 179 being positioned to be engaged by the cam when the gate and door reach fully closed position, see Figure 3.
- 635 An interlocking mechanism, designated as a whole by 71, is provided for each hatchway door, the interlocking mechanism being arranged to prevent operation of the elevator car except when all the hatchway doors are locked in closed position. Each interlocking mechanism comprises a casing 72 mounted in door casing 58 above the hatchway door. Casing 72 is positioned so that armature 63 is aligned therewith when the hatchway door is in closed position. Armature 63 is provided with projections 76, lugs 77 being provided within casing 72 for cooperation with projections 76 to prevent armature 63 being moved laterally with respect to casing 72 when the hatchway door is closed and armature 63 is in its lower position, see Figures 1 and 4. Thus, it will be seen that under these conditions the hatchway door can not be opened. A bridging contact 73 carried by the armature near its upper end engages a pair of contacts 75 when the armature is in its lower position. The contacts 75 of each of the interlocking mechanisms 71 are arranged in a control circuit for the elevator car, such as the starting circuit, to prevent the operation of the car when any hatchway door is unlocked.
- 640 The operating lever 158 of a gate switch, designated as a whole by 159, is arranged to be engaged by a roller 148 carried by the gate to effect closing of gate switch 159 when the gate is in closed position. Gate switch 159 is also arranged in a control circuit for the elevator car to prevent operation of the car when the gate is opened.
- 645 The operating lever 158 of a gate switch, designated as a whole by 159, is arranged to be engaged by a roller 148 carried by the gate to effect closing of gate switch 159 when the gate is in closed position. Gate switch 159 is also arranged in a control circuit for the elevator car to prevent operation of the car when the gate is opened.
- 650 Checking mechanism is provided to retard the gate and door in the latter part of the opening and closing movements thereof by motor 37. This mechanism is illustrated in Figures 1, 3 and 8, the details of the mechanism being shown in Figure 8. Referring to Figures 1, 3 and 8, a shaft 46 extends through bearing support 47 and is provided with a sprocket 96. This sprocket drives a chain 97 to operate shaft 98 through sprocket 100 thereon. Shaft 98 is journaled in bearings 101 on a plate 102 secured to support 24. A worm 103 is formed on shaft 98 between the bearings 101 and is adapted to cooperate with a traveller nut 104 carried by an extension 105 of a walking beam 106 pivotally supported on plate 102 at 107. Studs 108 secure the travelling nut 104 to the extension 105 to prevent the rotation of nut 104 with shaft 98 as the shaft is rotated. The nut, however, is free to turn upon the studs as beam 106 oscillates. The slots in extension 105, through which the studs extend, permit movement of the nut longitudinally of the extension as the

distance between the pivot of the beam and the pivot for the nut changes due to oscillation of the beam.

The beam 106, near one end thereof, pivotally supports a coupling member 110. This member has screw threaded engagement with a piston rod 111 of a check device 109 and is locked thereto by means of a lock nut 126. Piston rod 111 extends into piston cylinder 112 and has a piston 113 secured to its free end by a pin 114. Piston 113 fits snugly within the cylinder 112 and has a by-pass 115 therethrough provided with a ball check 116 which permits the liquid in the cylinder to flow from the side of the piston 113 to which the piston rod 111 is connected but prevents a reversal of the flow. The inner wall of cylinder 112 is provided with spaced longitudinal grooves 117. A by-pass 120 connects one longitudinal groove 20 with the ungrooved portion of the cylinder at a point adjacent a plug 118 which closes the lower end of piston cylinder 112. An adjustable needle valve 121 is provided near the upper end of by-pass 120 to regulate its effective area. A non-compressible fluid such as oil, is provided in piston cylinder 112, being introduced therein through a filling aperture closed by a plug 123. The bottom plug 118 of the piston cylinder has a tongue 125 pivotally supported between lugs on plate 102.

The other end of beam 106 is similarly connected to the piston rod of a check device 127. Check device 127 is of the same construction as check device 109 and will not be described.

The lock nuts 126 and coupling members 110 afford a means for adjusting the checking mechanism to accommodate closures having varying degrees of movement without changing the gear ratio of sprockets 96 and 100 or the pitch of worm 103.

The operation is as follows:—When magnets 50 are energized the lines of force emanating therefrom permeate plate 52 on the car gate to establish a magnetic connection between gate 26 and carriage 35 so that upon movement of the carriage the gate is moved therewith. The lines of force emanating from the magnets also act upon armature 63 on the adjacent hatchway door to attract the armature toward the carriage 35. The initial movement of armature 63 removes the bridging contact 73 from door lock contacts 75 opening the control circuits of the car to prevent operation of the car 21 by the hoisting motor during the gate and door opening operation. As the armature continues to move toward the carriage the projections 76 are moved away from the lugs 77 in the interlock housing, unlocking the hatchway door. The armature then enters the space between angles 51 and its leather surface 78 is drawn against the toothed rollers 80. As the armature is coupled to carriage 35 it strikes roller 82, rocking the bell crank 86.

Contact 88 is thus moved from engagement with contact 91 and into engagement with contact 92. The engagement of contacts 88 and 92 completes a circuit for causing motor 37 to operate the motor in a direction to move the carriage 35 to open the gate and door. The motor upon operation moves carriage 35 on track 30 and, through the lines of force emanating from magnets 50 which permeate plate 52 to establish a magnetic connection between the gate and carriage 35 and which maintain armature 63 coupled to the carriage, cause the gate 26 and door 54 to be moved toward open position. While the angles 51 and the teeth of rolls 80 on carriage 35 have been described as acting to insure against lateral motion of the carriage relatively to armature 63 as the carriage is moved, it is to be understood that these are precautionary features and that the lines of force emanating from magnets 50 act upon the armature 63 to cause movement of the hatchway door with the carriage as well as to attract the armature to the carriage.

In the initial movement of the carriage cam 171 rides from under the roller 179 allowing the contacts of switch 170 to engage. The initial movement of gate 26 causes the roller 148 to move from engagement with operating lever 158 permitting gate switch 159 to open.

At the beginning of the gate and door opening movement piston 113 is at the upper end of cylinder 112 adjacent the grooves 117. As the gate and door are opened shaft 98 is operated by chain 97. Rotation of shaft 98 moves travelling nut 104 to the right along worm 103. As nut 104 is secured to the walking beam 106 the latter is rocked clockwise about its pivot 107, thus moving piston 113 downwardly in cylinder 112. While the piston is moving in the grooved portion of the cylinder the liquid flows freely in the grooves from one side of the piston to the other, thus permitting free movement of the gate 26 and door 54 toward open position. When the gate and door are within a short distance of their fully open position piston 113 enters the ungrooved portion of cylinder 112 and its movement, as well as that of the gate and door, is immediately retarded. This retardation is due to the inability of the liquid to continue to pass around the piston through the grooves and to the action of ball check 116 which prevents the flow of liquid trapped between piston 113 and bottom plug 118 through the piston by-pass 115. As piston 113 continues to move, the trapped liquid must flow to the other side of the piston by way of by-pass 120. As the by-pass is restricted by needle valve 121 the flow occurs slowly and the gate, door and piston are retarded in their movement.

As the gate and door reach open position cam 171 on carriage 35 lifts the roller 169 of

switch 160, rocking lever 161 against the force of spring 166 to separate the contacts 164 and 165. This causes the circuits for motor 37 to be interrupted. As a result, the gate and door are brought to a stop, the checking device causing them to be brought to rest easily and quietly. The usual bumpers are provided to prevent undue coasting of the gate and door after the circuits of motor 37 are interrupted. Magnets 50 are also deenergized as switch 160 opens. As a result armature 63 moves by gravity toward the hatchway door, thus interrupting the coupling of the door to carriage 35. Movement of armature 63 away from the carriage also results in movement of contact 88 from engagement with contact 92 into engagement with contact 91, as previously described.

When it is desired to close the car gate and hatchway door magnets 50 are energized to couple the gate and door to the carriage. The attraction of armature 63 by magnets 50 causes contact 88 to move from engagement with contact 91 into engagement with contact 92, as previously described. Upon the engagement of contact 88 with contact 92 a circuit is completed to cause the energization of the motor 37 for reverse operation. The carriage 35 is moved by motor 37 and, as the carriage is magnetically coupled to gate 26 and door 54, the car gate and hatchway door move with the carriage toward their closed position. The initial movement of carriage 35 causes cam 171 to ride from under the roller 169 of switch 160 permitting contacts 164 and 165 of the switch to engage.

At the beginning of the gate and door closing operation piston 113 is adjacent plug 118 with its cylindrical portion in contact with the ungrooved portion of the cylinder wall. As the gate and door close the travelling nut 104 is moved to the left rocking the walking beam 106 counterclockwise and the piston starts to move away from plug 118. The resulting reduced pressure in the space between the inner end of piston 113 and plug 118 causes ball check 116 to open to permit liquid to flow into this space from above the piston through the by-pass 115 therein. At the same time a limited quantity of liquid flows into this space through by-pass 120. Thus, the resistance offered to the initial closing movement of the gate by the action of piston 113 within the ungrooved portion of cylinder 112 is negligible. When the piston is moved into the grooved portion of cylinder 112 the liquid flows freely through the grooves. Free movement of the gate and door toward closed position is thus permitted. However, as the fully closed position is approached, the gate and door are checked by the action of checking device 127. This device acts to retard the gate and door at the end of the closing operation in the same manner as previously de-

scribed for checking device 109 in the opening operation.

When the gate and door reach closed position the contacts of switch 170 are separated by engagement of the cam 171 with roller 179 causing the circuit for motor 37 to be interrupted and the movement of carriage 35 ceases. The gate in its final movement causes roller 148 to engage lever 158 effecting engagement of the contacts of gate switch 159. When magnets 50 are deenergized armature 63 is no longer attracted and falls back against the door 54. As armature 63 moves from between angles 51 it moves out of engagement with roller 82 permitting spring 90 to move contact 88 from engagement with contact 92 and into engagement with contact 91 in preparation for a subsequent operation.

As the armature continues to fall back, its projections 76 realign with the lugs 77 of the interlock housing to lock the hatchway door in closed position and immediately thereafter contact 73 bridges contacts 75.

Thus, it will be seen that, with the above construction, positive operation of the car gate and hatchway doors is effected, even though due to building construction or other causes variations in clearance may exist between the car and the door sills at the various floors. The magnetic gap between magnets 50 on the carriage and plate 52 on the car remains constant, unaffected by such variations in clearance, owing to the fact that both the gate and carriage 35 are carried by the car.

In case of the hatchway doors, however, such variations in clearance cause a corresponding variation to exist in the amount of magnetic gap between magnets 50 and armatures 63 on the hatchway doors at the various floors. The arrangement of movable armatures effectively obviates any possibility of faulty operation of the hatchway doors, the armatures simply being moved a greater distance in case of large clearances and a less distance in the case of small clearances. The armatures are moved to full attracted position in every case, so that the coupling of the doors to the closure operator on the car is positively effected and firmly maintained regardless of variations in clearance which may exist.

It is also to be noted that each armature 63 also serves as part of the interlock mechanism for the hatchway door for which it is provided. Thus, not only is the construction of the door operating and interlocking mechanism for each door simplified by such unitary arrangement but also an electromagnetic interlock is provided for each hatchway door with a single actuating electromagnet carried by the car for operating the various interlocks. Such arrangement is of particular advantage in present day electric elevator systems because of the resultant economy in space, low cost of manufacture, installation and operation, and the positive-

ness of operation under variations of operating conditions in the same or in different installations. Furthermore, the interdependence of the interlock mechanism and coupling mechanism provided in accordance with the above construction insures the opening of the circuit through the hatchway door contacts and the unlocking of the hatchway door before the hatchway door is connected to the hatchway door operating mechanism. Thus, any possibility of damage to the installation or injury to persons, due, for example, to the operation of the door and gate operating mechanism before rendering the control circuits ineffective and unlocking the hatchway door, is obviated.

The adaptation of the closure operating and interlocking mechanism to an elevator system in which the elevator car is controlled by an operator in the car is illustrated in Figure 10. A direct current control is shown although it is to be understood that the invention is applicable to alternating current systems. For convenience, a three floor installation will be described.

In Figure 10 the various electromagnetic switches employed in the system are designated as follows:—

A—Up direction switch,
 B—Down direction switch,
 P—Coupling magnet switch,
 X—Door and gate opening switch,
 Y—Door and gate closing switch,
 Z—Door and gate control switch.

Throughout the following description these letters in addition to the usual reference numerals will be employed when referring to parts related to the respective switches. For example, Y 183 designates contacts of the door and gate closing switch while coil B 155 is the actuating coil of the down direction switch for the elevator motor.

The hoisting motor for the elevator car and its associated mechanisms and the control circuits therefor have been omitted to simplify the description. The actuating coils of the elevator motor direction switches and the direction switch interlock contacts are shown to illustrate the action of the hatchway door interlock contacts and gate switch in the control circuits and to depict a suitable arrangement for obtaining a sequence between the door closing operation and the starting of the elevator car in response to operation of the car switch. The motor 37 which moves the carriage 35 to operate the gate and door is, for simplicity of illustration, shown as a series wound direct current motor. Its armature is designated 130 and its series field winding is designated 131. The numeral 132 designates a selector machine or similar mechanism actuated in accordance with car travel. Selector machine 132 is provided with cams 133, 134 and 135 adapted to cause the separation of the contacts 136 of a switch 137 when the elevator car is positioned within a certain zone with relation to the various landings, as for example, when the platform of the elevator car is three inches above or below the level of the landings. This zone will be hereinafter referred to as the "door operating zone". One of the contacts 136 is biased to engaged position with the other contact by a spring 138 acting on the switch lever. The numeral 140 designates a switch controlled by a governor responsive to car speed. Governor controlled switch 140 is arranged to prevent the coupling of the hatchway doors to carriage 35 when the elevator car is moving, as in or through the door operating zone, above a predetermined speed. The car switch is designated 141. The car switch is provided with the usual bridging segment and control contacts for the elevator motor control circuits and also with a member 144 having a pair of arcuate cam surfaces separated by a depression for receiving the roller 145 of an auxiliary door control switch 147 when the car switch is in neutral position.

Door lock contacts 75 arranged to be bridged by a contact 73 are provided for each hatchway door, these contacts being arranged in series relation and represented in Figure 10 by a single pair of contacts 75 together with the associated bridging contact 73. A manually operable switch 128 is provided in the car for effecting the deenergization of magnets 50 when desired. The numeral 149 designates a resistance the purpose of which will hereinafter be described. Wires 200 and 202 are connected to a suitable source of power supply.

The operation is as follows: Assume that the elevator car is at rest at the third floor with the car switch 141 in neutral position. The cam 133 on the floor controller which corresponds to the third floor is in engagement with the lever of switch 137, causing contacts 136 to be separated. As the car is at rest the governor controlled switch 140 is also open. Assume further that the car gate and the adjacent hatchway door are in open position. As a result, door limit switch 160, gate switch 159, and third floor door interlock switch 73, 75 are open and limit switch 170 is closed. The switches are illustrated in this condition in Figure 10.

Assume that a trip is to be made to the first floor. The elevator operator moves the car switch 141 in the counterclockwise direction from neutral position. The initial movement of the car switch causes the right-hand cam surface of member 144 to raise roller 145, thereby effecting the engagement of contacts 146 of the auxiliary door control switch. The engagement of contacts 146 completes a circuit from wire 200, through contacts 146, coil Z 178, to wire 202, for actuating coil Z 178 of the door control switch. The energization of coil Z 178 results in the engagement

of contacts Z 172 and Z 177 and the separation of contacts Z 173 and Z 176. The purpose of contacts Z 173 and Z 176 will appear as the description proceeds. The engagement of contacts Z 172 prepares the circuit for actuating coil Y 181 of the door closing switch. The engagement of contacts Z 177 completes the circuit for the coupling magnets 50. This circuit may be traced from wire 200, through contact 88, contact 91, magnets 50, switch 128, limit switch 170, contacts Z 177, contacts P 180, to wire 202.

As the magnets 50 on carriage 35 are in alignment with the armature 63 on the open hatchway door, the armature is attracted upon energization of the magnets coupling the hatchway door to the carriage as previously described. As the armature moves into position between the angle members 51 it strikes the roller 82 moving contact 88 from engagement with contact 91 into engagement with contact 92. The separation of contacts 88 and 91 removes the short circuit around resistance 149 thereby placing this resistance in series with the magnets 50. Resistance 149 acts to reduce the current passing through magnets 50, preventing overheating of the magnets and reducing current consumption.

The engagement of contacts 88 and 92 completes the circuit for actuating coil Y 181 of the gate and door closing switch. This circuit may be traced from wire 200, through contact 88, contact 92, contacts X 192 of the door opening switch, coil Y 181, contacts Z 172, contacts P 180, to wire 202. Coil Y 181 on energization effects the separation of contacts Y 182 and the engagement of contacts Y 183 and Y 184. Contacts Y 182 together with contacts Z 173 are in the circuit for actuating coil X 191 of the door opening switch, the separation of these contacts preventing energization of this coil. Contacts Y 182 together with contacts X 192 function as electrical interlocks. The engagement of contacts Y 183 and Y 184 completes the circuit for the armature and series field winding of the gate and door operating motor 37. This circuit is from wire 200, through contacts Y 183, armature 130, contacts Y 184, series field winding 131, to wire 202.

Upon energization of its windings, motor 37 is operated to move the carriage 35 in a direction to close the gate and hatchway door. As the car gate and hatchway door are coupled to carriage 35 by the lines of force emanating from magnets 50 they are moved with the carriage towards closed position. As the gate and door move from open position the cam 171 on carriage 35 moves from under the roller 169 permitting limit switch 160 to close. The closing of switch 160 establishes an additional circuit for magnets 50, this switch paralleling contacts Z 177 of switch Z. When the gate and door reach closed position the cam 171 on carriage 35

engages the roller 179 causing limit switch 170 to open. Upon the opening of switch 170 magnets 50 become deenergized thereby interrupting the magnetic connection of the gate and door to the carriage.

As the armature 63 is no longer attracted by magnets 50 it moves by gravity away from the carriage 35 and out of engaging relation with the roller 82 resulting in the movement of contact 88 from engagement with contact 92 into engagement with contact 91 as previously described. The separation of contacts 88 and 92 results in the deenergization of actuating coil Y 181 of the gate and door closing switch. Upon the deenergization of coil Y 181, contacts Y 182 engage and contacts Y 183 and Y 184 separate. The separation of contacts Y 183 and Y 184 results in the interruption of the circuit for armature 130 and series field 131 of gate and door operating motor 37 and the motor stops. The engagement of contacts Y 181 prepares the circuit of actuating coil X 191 for a gate and door opening operation. The engagement of contacts 88 and 91 short-circuits the resistance 149 to permit the full current value to pass through magnets 50 upon the initiation of a subsequent gate and door operation.

The armature 63 continues to move away from carriage 35 into juxtaposition with the rear surface of the hatchway door 54 and successively locks the hatchway in closed position and moves contact 73 into bridging relation with the door contacts 75 as previously described. As the car gate reaches closed position gate switch 159 closes. The closing of gate switch 159 together with the bridging of door lock contacts 75 by contact 73 prepares the circuits for the actuating coils of the direction switches of the hoisting motor.

Upon further counterclockwise movement of car switch 141 from neutral position segment 142 bridges contacts 153 and 154 completing the circuit for the actuating coil B 155 of the elevator motor down direction switch. The circuit for coil B 155 may be traced from wire 200, through door lock contacts 75, gate switch 159, coil B 155, contact 153, segment 142, contact 154, contacts A 156 of the up direction switch, to wire 202. The energization of coil B 155 effects the separation of contacts B 157. The separation of contacts B 157 of the down direction switch opens the circuit for the actuating coil A 152 of the up direction switch. These contacts together with contacts A 156 serve as electrical interlocks for the circuits of the actuating coils of the direction switches. Other contacts, not shown, are provided on the down direction switch, the energization of coil B 155 causing these contacts to assume positions effecting the starting of the elevator car in the down direction. A sequence relay may be provided, if desired, to prevent the starting of the car on the door and gate contacts.

Such a relay is known in the art and is arranged to prevent the starting of the car in the event that contacts 153 and 154 are bridged before the door and gate are closed and the related contacts are engaged. To simplify the description such an arrangement is not shown.

With the car switch in the full on position control mechanisms are operated to cause the car to be brought up to full speed. As the car leaves the third floor and passes beyond the door operating zone the lever of switch 137 disengages cam 133 to permit spring 138 to effect the engagement of contacts 136. The engagement of contacts 136 completes a circuit for actuating coil P 190 of the coupling magnet switch. The energization of coil P 190 results in the separation of contacts P 180, further opening the circuit for coupling magnets 50. When the elevator car reaches a predetermined speed, the contacts of governor controlled switch 140 are bridged to establish an additional circuit for coil P 190.

When the elevator car arrives within the door operating zone at the second floor the operation of selector machine 132 effects the separation of contacts 136 by the engagement of cam 134 and the lever of switch 137. As a stop is not to be made at the second floor the car is moving above the speed at which governor switch 140 opens so that coil P 190 is not deenergized by the separation of contacts 136 as the car passes the second floor.

Upon approaching the first floor the operator moves the car switch from full on position to neutral position causing the stopping of the car. When the car switch is moved to neutral position, the roller 145 of switch 147 falls into the depression between the cam surfaces of member 144 resulting in the separation of contacts 146. Upon separation of contacts 146, coil Z 178 is deenergized and contacts Z 172 and Z 177 separate while contacts Z 173 and Z 176 engage. The separation of contacts Z 172 interrupts the circuit for coil Y 181 of the gate and door closing switch. The engagement of contacts Z 173 prepares the circuit for actuating coil X 191 of gate and door opening switch. The separation of contacts Z 177 interrupts the circuit by passing the limit switch 160. The engagement of contacts Z 176 by-passes limit switch 170.

It will be assumed that on or before reaching the door operating zone at the first floor the speed of the car has decreased sufficiently to cause governor controlled switch 140 to open. As the car arrives within this zone, switch 137 opens as the switch lever engages cam 135. The opening of this switch together with the opening of governor switch 140 causes the deenergization of coil P 190. Contacts P 180 engage and complete a circuit for coupling magnets 50 through contacts Z 176 and limit switch 160.

Magnets 50 upon energization attract ar-

mature 63 to move contact 73 from engagement with door lock contacts 75, unlock the hatchway door at the first floor, couple the hatchway door to carriage 35 and effect the movement of contact 88 from engagement 70 with contact 91 into engagement with contact 92, all as previously described. When contact 73 is moved out of engagement with contacts 75 the circuit for the actuating coils A 152 and B 155 of the direction switches of the elevator motor is opened. Upon engagement of contacts 88 and 92 the circuit for coil X 191 of the gate and door opening switch is completed through contacts Y 182, Z 173 and P 180, resulting in the separation of contacts 80 X 192 and the engagement of contacts X 193 and X 194. The separation of contacts X 192 opens the circuit of coil Y 181 to prevent operation of the gate and door closing switch. The engagement of contacts X 193 and X 194 85 completes the circuit for the armature 130 and series field winding 131 of the gate and door operating motor 37. This circuit may be traced from wire 200, through contacts X 193, armature 130, contacts X 194, series field 90 winding 131, to wire 202.

The circuit for the armature of motor 37 being reversed from that previously traced the motor operates to move carriage 35 and the car gate and hatchway door toward open 95 position. As the car gate and hatchway door are moved from closed position the cam 171 on carriage 35 moves out of engagement with roller 179 permitting the switch 170 to close. The closing of switch 170 completes an additional circuit for magnets 50 paralleling contacts Z 176. As the gate is moved from closed position the roller 148 carried thereby moves out of engagement with lever 158 and gate switch 159 opens further interrupting the 105 circuit for coils A 152 and B 155.

When the gate and door reach open position the cam 171 engages roller 169 thereby causing limit switch 160 to open. The opening of switch 160 results in the deenergization 110 of the coupling magnets 50. Armature 63 on the hatchway door at the first floor, no longer held against carriage 35 by the field of magnets 50, moves by gravity away from the carriage into juxtaposition with the rear 115 surface of the door. As the armature 63 moves away from the carriage 35 it moves out of engagement with roller 82 permitting contact 88 to move from contact 92 into engagement with contact 91. The engagement of 120 contacts 88 and 91 by-passes resistance 149 as previously described. The separation of contacts 88 and 92 results in the deenergization of actuating coil X 191. As the coil X 191 is deenergized, contacts X 192 engage 125 and contacts X 193 and X 194 separate. The separation of contacts X 193 and X 194 interrupts the circuits for the armature 130 and series field winding 131 of gate and door operating motor 37 and the latter stops. The 130

engagement of contacts X 192 prepares the circuit for coil Y 181 of the gate and door closing switch.

After initiating the operation of motor 37 to close the car gate and hatchway door, the closing movement may be interrupted and the gate and door returned to open position by moving the car switch back to neutral position. This effects the deenergization of switch Z 178 breaking the circuit for coil Y 181 of the door closing switch and completing the circuit for coil X 191 of the door opening switch. This causes the door operating motor to be reversed to return the door and gate to open position, the circuit for coupling magnets 50 being maintained through limit switches 160 and 170 to maintain the door and gate coupled to the carriage. Similarly, after initiating the operation of motor 37 to open the car gate and hatchway door by movement of the car switch to neutral position, the opening movement may be interrupted and the gate and door returned to closed position by moving the car switch in either direction from neutral position. This effects the energization of switch Z 178 breaking the circuit for coil X 191 of the door opening switch and completing the circuit for coil Y 181 of the door closing switch. As a result, motor 37 is reversed, returning the door and gate to closed position, the coupling magnets being maintained energized, as before, through limit switches 160 and 170.

If it is desired to maintain the car gate and hatchway door coupled to carriage 35 while the gate and door are in open position, the limit switch 160, which is opened when the gate and door reach open position, may be removed from the circuit of magnets 50. The contacts Z 177 may then be omitted from the circuit of magnets 50 as their function is to by-pass the switch 160 to permit the gate and door to be coupled to the carriage 35 and moved from open position. When this arrangement is employed to maintain the magnetic coupling between the car gate, hatchway door and carriage 35, limit switch 160 is arranged to interrupt the circuit for coil X 191 of the gate and door opening switch to stop motor 37 when the gate and door reach open position.

The manually operable switch 128 in the elevator car is provided to permit deenergization of coupling magnets 50 when desired. Thus, by operating switch 128 and deenergizing the magnets, the gate and door may be operated by hand without manually exerting additional force to operate motor 37 and the mechanism connected thereto. In case of manual operation the interlocking mechanism may be released by upward movement of armature 63 through the intermediary of rod 68. The provision of the arrangement for permitting deenergization of magnets 50 is of particular advantage in case motor 37

becomes out of order and is also of advantage in that it permits the door and gate to be maintained in open position for a considerable period without having the magnets energized in cases where the deenergization of magnets 50 when the gate and door are in open position is not normally effected.

It is to be understood that levelling mechanism may be provided to effect exact landing stops, and the control circuits may be arranged to permit the opening of the door and gate during the levelling operation. In case of systems in which the stopping of the car at the landings is under the control of the passengers themselves, the control circuits may be arranged to prevent the opening of the door and gate until the car has been stopped at the landing, such as by controlling the door and gate operating mechanism in the stopping operation by a selector machine or other mechanism actuated in accordance with car movement.

It is to be noted that the operation of motor 37 to move carriage 35 to open or close the gate and door is dependent upon the operation of the switching mechanism on the carriage by the armature on the hatchway door. Thus, the motor 37 is ineffective to operate the carriage and the door and gate unless the door is properly connected to the carriage.

While the invention has been described as applied to an elevator system in which both the starting and stopping of the car is under the control of an operator in the car, it is to be understood that such system has been chosen merely to illustrate the principles of operation of the invention. The invention is also applicable to systems in which the starting of the car is under the control of an operator in the car with the stopping of the car automatically effected, and to systems in which both the starting and stopping of the car, or only the stopping thereof, is under the control of the passengers and intending passengers themselves. Also, manually operable control switches may be provided for controlling the operation of the gate and door operating mechanism.

According to the embodiment of the invention described, the carriage, car gate and hatchway door have been described as operated by the motor 37 in both the opening and closing direction. It is to be understood, however, that other arrangements may be employed such as utilizing motor 37 for the opening operation with the mechanism biased to closed position and such as employing other forms of motive means in place of the operating motor illustrated.

As many changes could be made in the above construction and many apparently widely different embodiments of this invention could be made without departing from the scope thereof, it is intended that all matter contained in the above description or

shown in the accompanying drawings shall be interpreted as illustrative and not in a limiting sense.

What is claimed is:

5. 1. In an elevator installation; and elevator car; closure means for affording access to said car; an armature carried by said closure means; an electromagnet for said armature; means for moving said electromagnet in the direction of movement of said closure means; and means responsive to said electromagnet, upon energization thereof, for causing the operation of said moving means to move said electromagnet, said moving means, upon operation, acting solely through the lines of force between said electromagnet and said armature to move said closing means.
2. In an elevator installation; an elevator car; closure means which when open affords access to said car; means for operating said closure means, said operating means being disconnected from said closure means; an electromagnet connected to said operating means for movement thereby; an armature for said electromagnet connected to said closure means and attractable by said electromagnet to couple said closure means to said closure operating means; and circuit controlling means operated by said armature upon attraction thereof by said electromagnet.
3. In an elevator installation; an elevator car; closure means which when open affords access to said car; means for operating said closure means, said operating means comprising a magnet; a movable armature for said magnet carried by said closure means, said armature being movable by the attraction of said magnet into a position to couple said closure means to said operating means for operation thereby; and means operated by said armature, upon its movement to said position, for causing said operating means to operate said closure means.
4. In an elevator installation; an elevator car; closure means which when open affords access to said car; means for operating said closure means, said operating means being disconnected from said closure means; an electromagnet connected to said operating means for movement thereby; an armature for said electromagnet connected to said closure means and movable by said electromagnet to couple said closure means to said closure operating means; and means controlled by said armature for preventing the operation of said operating means until said closure means has been coupled to said operating means by the attraction of said armature by said magnet.
5. In an elevator installation; an elevator car; a car gate; a hatchway door; a motor carried by said car; a carriage carried by the car, said carriage being movable transversely of the openings closed by said gate and door and being disconnected from said
- gate and door; means for connecting said carriage to said motor to be moved thereby; an electromagnet carried by said carriage; an armature carried by said gate and an armature carried by said door, said armatures, upon energization of said electromagnet, being acted upon by the magnetic field of said electromagnet to couple said gate and door to said carriage for movement therewith by said motor; and circuit controlling means operated by said electromagnet upon the coupling of said gate and door to said carriage for causing the energization of said motor.
6. In an elevator installation; an elevator car; closure means which when open affords access to said car; means for operating said closure means, said operating means comprising a motor and a magnet; a movable armature for said magnet carried by said closure means, said armature being movable by the attraction of said magnet to a position to couple said closure means to said operating means for operation thereby; and circuit controlling means for said motor operable by said movable armature, upon its movement to said coupling position, for causing energization of said motor to operate said closure means.
7. In an elevator installation; an elevator car; closure means which when open affords access to said car; means for operating said closure means; coupling means operable to couple and uncouple said closure means to said closure operating means; and interlocking mechanism for said closure means, said interlocking mechanism comprising circuit controlling means and means for locking said closure means and being operable by said coupling means to open said circuit controlling means and to unlock said closure means prior to the coupling of said closure means to said closure operating means.
8. In an elevator installation; an elevator car; closure means which when open affords access to said car; means for operating said closure means; coupling means operable to couple and uncouple said closure means to said closure operating means; and locking mechanism for said closure means operated by said coupling means to unlock said closure means prior to the coupling of said closure means to said closure operating means.
9. In an elevator installation; an elevator car; closure means for affording access to said car; means for operating said closure means, said operating means being uncoupled from said closure means; a magnet for coupling said closure means to said operating means, for operation thereby; and interlocking mechanism for said closure means, said interlocking mechanism comprising circuit controlling means and means for locking said closure means and being operable by said magnet to open said circuit controlling means

and to unlock said closure means prior to the coupling of said closure means to said closure operating means.

10. In an elevator installation; an elevator car; closure means for affording access to said car; means for operating said closure means, said closure means being disconnected from said closure operating means; a movable armature carried by said closure means; means cooperating with said armature to lock said closure means; circuit controlling means operable by said armature; and a magnet for causing movement of said armature to operate said circuit controlling means, unlock said closure means and connect said closure means to said closure operating means.

11. In an elevator installation; an elevator car; closure means for affording access to the car; a movable armature carried by said closure means; operating mechanism for said closure means disconnected therefrom; an electromagnet connected to said operating mechanism for movement thereby, said electromagnet upon energization attracting said armature to a position to couple said closure means to said operating mechanism; switching mechanism operated by said armature upon attraction thereof by said electromagnet prior to the coupling of said closure means; to said operating mechanism; and locking means for said closure means operated by said armature upon attraction thereof by said electromagnet to unlock said closure means, said locking means also being operated prior to the coupling of said closure means to said operating mechanism but subsequent to the operation of said switching mechanism.

12. In an elevator installation; an elevator car; closure means for affording access to the car; a movable armature carried by said closure means; operating mechanism for said closure means disconnected therefrom; an electromagnet connected to said operating mechanism for movement thereby, said electromagnet upon energization attracting said armature to a position to couple said closure means to said operating mechanism; switching mechanism operated by said armature upon attraction thereof by said electromagnet net prior to the coupling of said closure means to said operating mechanism; locking means for said closure means operated by said armature upon attraction thereof by said electromagnet to unlock said closure means, said locking means also being operated prior to the coupling of said closure means to said operating mechanism but subsequent to the operation of said switching mechanism; and additional switching mechanism operable by said armature upon attraction thereof by said electromagnet when the coupling of said closure means to said operating mechanism is effected.

13. In an elevator installation; an elevator car; closure means for affording access to

said car; a motor; a carriage movable transversely of the opening closed by said closure means, said carriage being disconnected from said closure means; means connecting said carriage to said motor for operation thereby; a movable armature carried by said closure means; an electromagnet for said armature on said carriage; said electromagnet, upon energization, acting through the intermediary of its magnetic field on said armature to move said armature to couple said closure means to said carriage for movement thereby; and angle members on said carriage for receiving said armature therebetween, each of said angle members being adapted to be engaged by said armature, in the event of lateral motion of said carriage relatively to said armature, for preventing breaking of the coupling of said closure means to said carriage once said coupling has been effected.

14. In an elevator installation; an elevator car; closure means for affording access to said car; a motor; a carriage movable transversely of the opening closed by said closure means, said carriage being disconnected from said closure means; means connecting said carriage to said motor for operation thereby; a movable armature carried by said closure means; an electromagnet for said armature on said carriage, said electromagnet, upon energization, acting through the intermediary of its magnetic field on said armature to move said armature to couple said closure means to said carriage for movement thereby; angle members on said carriage for receiving said armature therebetween, each of said angle members being adapted to be engaged by said armature, in the event of lateral motion of said carriage relatively to said armature, for preventing breaking of the coupling of said closure means to said carriage once said coupling has been effected; angle members on said carriage for receiving said armature therebetween, each of said angle members being adapted to be engaged by said armature, in the event of lateral motion of said carriage relatively to said armature, for preventing breaking of the coupling of said closure means to said carriage once said coupling has been effected; and anti-friction means mounted on said carriage between said angle members, said anti-friction means cooperating with said armature, to permit up or down movement of said carriage relatively to said armature without undue friction, when said closure means is coupled to said carriage.

15. In an elevator installation; an elevator car; a hatchway door; a gate on said car; an electric motor carried by the car; a carriage slidably mounted on said car for movement in the direction of movement of said door and gate, said carriage being disconnected from said gate and door; means connecting said carriage to said motor for movement thereby; an armature carried by said gate, an armature pivotally mounted on said door; angle members mounted on said carriage for receiving said pivoted armature therebetween; a switch on said carriage for controlling said motor; a lever for operating said switch having a roller positioned between said angle members; electromagnets

- mounted on said carriage having their pole pieces positioned between said angle members, said electromagnets on energization acting through the intermediary of the lines of force emanating therefrom to said armature carried by the gate to couple said gate to said carriage and acting to attract said armature on said door to a position between said angle members, said armature on said door, upon being removed to said position between said angle members, engaging said roller to operate said switch, said angle members preventing breaking of the coupling between said carriage and door in the event relative movement of said angle members and said armature on the door occurs; sound deadening means on the face of said armature on the door; and anti-friction rollers mounted on said carriage between said angle members to be engaged by said sound deadening means on said armature, the faces of said rollers being serrated in the direction of movement of said car to permit movement of said car with respect to said door without undue friction and to aid in maintaining the coupling of said armature on said door to said carriage.
16. In an elevator installation; a hatchway; an elevator car therein; a landing served by said car; means for moving said car in said hatchway and for stopping it at said landing; a hatchway door at said landing which when open affords access to said car; means for operating said hatchway door, said operating means comprising a carriage slidably mounted on said car and being disconnected from said door; a motor for moving said carriage; a lock member for said door; an armature pivotally mounted on said door for cooperating with said lock member to lock said door in closed position; a switch operable by said armature, when said door is locked, for enabling movement of said car moving and stopping means; an electromagnet adapted upon energization to move said armature for unlocking said door, for operating said switch to prevent movement of said car by said car moving and stopping means and for coupling said door to said car for movement therewith; a switch operable by said armature, when the coupling of said door to said carriage has been effected, for energizing said motor to move said carriage; said first mentioned switch being operated prior to the operation of said second mentioned switch; means for energizing said electromagnet upon the arrival of said car to stop at said landing; and manually operable means for operating said first mentioned switch to prevent movement of said car, for unlocking said door and for operating said door.
17. In an elevator installation; a hatchway; an elevator car therein; a landing served by said car; means for moving said car in said hatchway and for stopping it at said landing; a hatchway door at said landing which when open affords access to said car; means for operating said hatchway door, said operating means comprising a carriage slidably mounted on said car and being disconnected from said door; a motor for moving said carriage; a lock member for said door; an armature pivotally mounted on said door for cooperating with said lock member to lock said door in closed position; a switch operable by said armature, when said door is locked, for enabling movement of said car moving and stopping means; an electromagnet adapted upon energization to move said armature for unlocking said door, for operating said switch to prevent movement of said car by said car moving and stopping means and for coupling said door to said car for movement therewith; a switch operable by said armature, when the coupling of said door to said carriage has been effected, for energizing said motor to move said carriage; said first mentioned switch being operated prior to the operation of said second mentioned switch; and means for energizing said electromagnet upon the arrival of said car to stop at said landing.
18. In an elevator installation; a hatchway; an elevator car therein; a landing served by said car; means for moving said car in said hatchway and for stopping it at said landing; a hatchway door at said landing which when open affords access to said car; means for operating said hatchway door, said operating means comprising a carriage slidably mounted on said car and being disconnected from said door; a motor for moving said carriage; a lock member for said door; an armature pivotally mounted on said door for cooperating with said lock member to lock said door in closed position; a switch operable by said armature, when said door is locked, for enabling movement of said car moving and stopping means; an electromagnet adapted upon energization to move said armature for unlocking said door, for operating said switch to prevent movement of said car by said car moving and stopping means and for coupling said door to said car for movement therewith; a switch operable by said armature, when the coupling of said door to said carriage has been effected, for energizing said motor to move said carriage; said first mentioned switch being operated prior to the operation of said second mentioned switch; and means for energizing said electromagnet upon the arrival of said car to stop at said landing.
